UNITED STATES PATENT OFFICE

ARTHUR YANCEY, OF NEW ORLEANS, LOUISIANA

MACHINE FOR MAKING AND SETTING ONE-PIECE CAN LINERS

Application filed April 5, 1922. Serial No. 549,874.

My invention relates to machines for making and setting one-piece can liners in which the liner is automatically wound from a liner magazine upon a liner form over which and over the wound and folded liner the can to be lined is telescoped and from which the can and liner are removed with the liner folded at its bottom and set within the can ready to receive the contents to be packed.

The main object of the invention is to provide automatic mechanism to make, fold and set the liners.

Other objects will appear.

The following is a description of a simple form of the invention and its operation:

Fig. 1 is a view of the entire machine, part in section and part in front elevation. The section is indicated in Figure 2 by the line 1—1.

Fig. 2 is a horizontal view with two sections indicated in Figure 1 respectively by the lines 2—2 and 2'—2' and distinguished by fine and coarse section lines, the forming 25 rotating gears being shown in section on the line 2—2 and the folders being shown in section on the lower plane of the line 2'—2'.

Fig. 3 shows a horizontal section indicated in Figure 1 by the line 3—3.

Fig. 4 shows a horizontal section indicated in Figure 1 by the line 4—4.

Fig. 5 shows a detail section of the liner form, pilot and folder, on lines 5—5 of Figures 8 and 10, and on the plane indicated by the line 5—5 in Fig. 6.

Fig. 6 is a horizontal section on line 6—6 of Fig. 5.

Fig. 7 is a vertical section on line 7—7 of Fig. 9.

Fig. 8 is a horizontal section on line 8—8 of Fig. 5.

Fig. 9 is a horizontal section on line 9—9 of Fig. 7.

Fig. 10 is a horizontal section on line 10—10 of Fig. 5.

Fig. 11 is a horizontal section on line 11—11 of Fig. 5.

Fig. 12 is a horizontal detail section of

the liner magazine indicated by the line 12—12 in Figure 13.

Fig. 13 is a vertical section of the liner magazine indicated by the line 13—13 in Figures 12 and 14.

Fig. 14 shows a developed circular section at the inner end of the liner magazine and one of the can holders, on the line indicated by the arc 14—14 in Figure 12, and by the vertical line 14—14 in Fig. 13.

Fig. 15 is a detail section on line 15—15 of Figs. 18 and 19.

Fig. 16 is a side view of the lower part of the liner rolled on the former.

Fig. 17 is a vertical section on line 17—17 of Fig. 15.

Fig. 18 is a plan view of the parts shown in Fig. 15.

Fig. 19 is a plan view of the parts shown in Fig. 16. Figs. 15 to 19 show the parts positioned for the first step in folding the bottom of the liner.

Fig. 20 is a vertical section on line 20—20 of Fig. 22.

Fig. 21 is a vertical section of the folder on line 21—21 of Fig. 20.

Fig. 22 is a plan view of the parts shown in Fig. 20. Figs. 20 to 22 show the performance of the first folding step.

Fig. 23 is a vertical section on line 23—23 of Fig. 25.

Fig. 24 is a vertical section of the folder on line 24—24 of Fig. 23.

Fig. 25 is a plan view of the parts shown in Fig. 23.

Figures 23 to 25 show the performance of the second step of folding.

Figs. 26 to 28 are similar detail views showing the performance of the third step.

Figs. 29 to 31 are similar detail views showing the performance of the fourth step.

Fig. 32 is a section showing an alternate arrangement for operating the folders which dispenses with the folder-lever and is preferable in a large machine where space for the cams required can be obtained. Fig. 33 is a section of the bellows cam track indicated in Figure 3 by the line 33—33.

A suitable frame is constructed to include

three plates 15, 16 and 18 and seven revol-
uble discs 19, 20, 22, 23, 25, 26 and 28.

The discs aforesaid are secured to a main
shaft which is driven by any suitable mech-
anism and is revoluble in bearings support-
ed by the plates as shown.

The liners *b* preferably consist of rec-
tangular sheets of parchment paper cut to a
length equal to the circumference of the can
10 plus allowance for the side lap and to width
equal to the height of the can plus allow-
ance for the lap on the top and bottom of
the can.

The liner magazine is secured to the frame
15 aforesaid at 29, figures 2, 4, 12 and 13, in
which a follower 31 is drawn back against
the compression spring 32, bearing against
a fixed plate 31', to insert the liners. When
the follower is released, the liners are
20 pressed against the corner clips 33, which
should be very thin or needle-like, and the
center clip 34, Figures 12, 13 and 14. The
curvature of the follower 31 is adapted to
hold the outside liner or that one positioned
25 for action in an arc adjacent to the path of
the rotary liner form 36.

The present form of the invention is ar-
ranged in six units, all alike, each having a
liner form 36.

30 One of these units and its cycle of opera-
tions will be described.

The unit approaches the liner magazine
29, say at A.

Above the can-holders 35 and concentric
35 therewith is a liner form 36 mounted on the
hollow form shaft 37 (Fig. 5) and connect-
ed with bellows 38, the bottom of the latter
being secured to the disc at 39.

The path of the liner form 36 is adjacent
40 to the exposed liner in the magazine, or that
liner ready for action, and the liner form is
positioned vertically by the magazine 29
to allow for the top and bottom laps.

Advancing from A, the air holes 40, Fig-
45 ure 5, are presented to the exposed liner
with a margin of about one inch.

Here, at B, the bellows cam track 41,
Figures 1 and 3, is elevated and the bellows
cam spring 42 forces the bellows cam follow-
50 er 43 to open the bellows 38 and air is
thereby drawn into the bellows through the
air chamber 44, Figure 5, at the holes 40
under the suction valve 45 and the margin
55 of the liner is pulled from the magazine
and held to the liner form 36 over the air
holes 40.

Form gear 46 is secured to the form shaft
37 and mates with and successively engages
60 the sections of gears secured to the gear band
47 and adjustably spaced apart at 48, 49, 50
and 51.

From B, the liner form revolves and the
liner is wound on the liner form.

65 A stuffing box 52 facilitates revolution

of the form shaft 37 without breaking the
suction.

The diameter of the pitch circle of the
form-gear 46 should equal the diameter of
the form to harmonize the winding of the
liner on the liner form with unwinding from
the magazine. Otherwise the liner will
rumple.

The can holder 35 is formed to provide
a cam 53, Figures 4, 12, 13 and 14, which
engages its mate 54 in passing along the
path indicated by the dotted line in Fig.
14, Figures 13 and 14, to depress the maga-
zine center clip 34 and allow the unwinding
70 of the liner from the magazine while the
form is passing the clip, after which the
latter springs up and returns to its normal
position and holds the next liner in place.
It will be understood that the cam 53, travel-
ing with its can holder, extends far enough
75 out at a proper level to depress the cam 54
and attached spring arm and clip 34 and
release the can-liner which is being rolled
up on the former, which is in axial line
80 with and above said can holder.

The form gear 46 has twelve teeth and
the first gear section 48 has twenty-one
teeth, the first three of which are provided
to turn the air holes 40 fairly to the margin
of the liner as described, and the next twelve
85 to turn the liner form one complete revo-
lution during which the liner is held to
the liner form entirely by suction. At this
point the cam 56 (Fig. 5) declines and the
roller 57 together with the hood rod 58
90 and sliding hood 59 are let down so the
liner is held on the form by the hood clip
60 (Fig. 7). The remaining six teeth in
the gear section 48 turn the liner form 36
half revolution so that the air holes 40 and
95 the lap 61 of the liner face the folder head
62 positioned for the first step in folding
the liner as shown in Figures 15, 16, 17, 18
and 19.

The folder head 62 is supported by the
100 folder bar 63 slidingly mounted in the folder
guides 64.

From C the folder cam follower 65 is
moved inwardly at 66 (Fig. 2) and the
105 folder bar 63 is moved outward by means
of the folder cam lever 67 pivotally secured
to the disc at 68.

Thus while advancing from C to D the
folder head 62 performs the first step in
110 folding the liner as shown in Figures 20,
21 and 22.

From D to E the form gear 46 provided
with twelve teeth engages the second gear
section 49 with six teeth and the liner form
115 36 makes half turn while the folder head
62 remains inactive.

The pilot head 69 mates with notches 70
in the pilot flange, Figures 1, 5 and 8, and
insures accurate positioning of the liner
form 36 for action of the folder head 62.

From E to F, the folder head 62 co-operating with the folder cam follower 65 and the folder cam lever 67, makes the second step in folding the liner as shown in Figures 23, 24 and 25.

From F to G, the liner form 36, co-operating with the other parts as described, makes a quarter turn.

From G to H, the folder head 62 makes the third step in folding the liner as shown in Figures 26, 27 and 28.

From H to I, the form gear 46 engages six teeth of the gear section 51 and the liner form 36 makes a half turn.

From I to J, the folder head 62, co-operating with the other parts as described, makes the fourth and the last step in folding the liner as shown in Figures 29, 30 and 31.

By changing the engagement of the notches 70 with the head 69, the inward movement of the cam roller 65 may be increased to increase the outward movement of the folder head 62 to press down and smooth the folds 71 and 72 with the flat part of the surface of the folder head as shown, Figure 31.

At K, Figure 4, the can to be lined is received by the can holder 35. The dotted lines show the position of disc 4 above the section plane, Figure 4.

73 is a moving belt, 74 shows the rail of the can race and 75 is a spring over which the can holder 35 passes and by which the next can is positioned to be received by the can holder of the next unit.

At L, the can-lift cam 76 begins to lift the can-lift roller 77 compressing the can-lift spring 78 and raising the can-lift 79 through the can-lift slot 80, Figure 4, and impales the can on the liner form 36.

At M, Figure 3, the bellows cam 41 depresses the bellows roller 43 producing an air blast from the bellows through the form shaft 37, Figures 1, 5 and 10, to the liner form 36 and through the blast valve 81 (Figs. 5 and 10) into the can expanding the liner to full contact with the sides and edges of the can.

At N, the can-lift cam 76 declines and lets down the can-lift 79. Co-incidently the continued depression of the bellows 38 and the consequent air blast aforesaid forces off the can with the liner set and expanded around within the sides and bottom edges of the can.

At O, the lined can is released on the discharge disc 82 and the cycle is repeated.

After the can has been filled, any suitable machine can be used to close the liners over the food to be canned, or the folding may be performed by hand.

A simple form of apparatus has been selected to illustrate the invention, but many

changes can be made without departing from its substance.

I claim and desire to protect by Letters Patent all combinations including all of the same or equivalent elements set forth in the following claims:

1. In a machine of the character described revoluble frame having a series of revoluble liner forms, means for supplying paper to said forms, air suction devices for attaching the paper to said forms for the winding of it thereon to form can-liners, means for rotating the forms upon the attachment of the paper thereto, means for receiving can receptacles on said frame arranged in line with said forms, means for folding the end of the wound liners before insertion of them into the cans, means for causing the cans to envelop said folded liners, and means for causing air pressure within the liners when they are separated from said forms.

2. In a machine for lining cans with paper or the like, the combination of a revoluble liner form, means for supplying sheets thereto to be rolled up into the form of liners, means for intermittently rotating said form, automatic devices for folding the end portion of the liner across the end of the form in the intervals between the turning movements of the form, and means for applying cans over the ends of the form and liners folded thereon.

3. In a machine for lining cans with paper or the like, the combination of a revoluble liner form, means for supplying sheets thereto to be rolled up into the form of liners, means for intermittently rotating said form, automatic devices for folding the end portion of the liner across the end of the form in the intervals between the turning movements of the form, means for applying cans over the ends of the forms and liners folded thereon, and air-forcing means for alternately drawing the paper against said form and forcing it therefrom.

4. The method of making and setting one-piece liners in cans comprising wrapping the liner around a form with the liner extending from the free end of the liner-form towards the supported end thereof as far as the sum of the widths of those parts of the said liner required to line the top and side, of a corresponding can, and extending from said free end thereof in opposite direction as far as the width of that part required to cover the bottom only of said can, bending successively with a mechanically operated folder parts of the free end of said liner over the end only of said liner form, pressing or crushing between the end of the liner form and the bottom of the can ears or flaps resulting from folding the liner, thus molding the flaps and folds to shape of the can, setting the liner therein and then withdrawing the can from the form with the liner set.

5. In a machine for making can liners, the combination of a liner form and a folder having a rounded part and adapted to operate on the end portion of the liner which projects beyond the form, means for causing said folder to operate in a substantially radial direction and across successive segments of the end of the liner and in a direction inward from the periphery to the middle of the liner until the end of said form is covered with rounded or arched folds and means for causing the liner to be enveloped within the can. 70
6. A machine for making and setting one-piece can liners including a liner-form; means to apply paper or the like to be shaped into liners thereon with divisions of the liner provided for its top and side closures covering said form and a division provided for the bottom closure extending beyond the end thereof to cover, when folded, the end only of the form; an automatic folder adapted to complete the bottom closure by successively bending parts of the extending liner over the end only of said form; means for telescoping a can over the liner-covered form; means for pressing, between the end of said form and can bottom, ears and flaps differently extending beyond the end of the form, to mold said ears and flaps to the shape of the can and means to remove the can with the liner set. 80
7. In apparatus for lining receptacles, the combination of a revoluble frame, means for imparting non-intermittent motion to said frame, a liner form and mechanical devices for folding the end closed of a liner shaped thereon, the said form and folding devices carried by said frame. 85
8. In apparatus for lining receptacles, the combination of a revoluble frame, a revoluble liner form and mechanical devices for folding the end of a liner to be shaped thereon, the said form and folding devices carried by said frame. 90
9. In apparatus for lining receptacles, the combination of a revoluble liner form, means for revolving said form for applying paper to be shaped into liners thereon, means for folding the ends of the liners, means for causing said liners to be enveloped within receptacles for lining the same and means to remove said receptacles with the liners set. 95
10. In apparatus for lining receptacles, the combination of a revoluble frame, a plurality of revoluble liner forms carried by said frame, means for rotating said forms automatic devices carried by said frame for folding the ends of liners shaped on said forms, means for causing the liners to be enveloped within said receptacles for lining same and means for removing said receptacles with the liners set. 105
11. In a machine for making and setting one-piece can liners, the combination of a revoluble frame and means adapted to move synchronously therewith including: a liner form, means for applying paper to be shaped into liners thereon, automatic devices for folding the ends of the liners, means for causing said liners to be enveloped within cans to line same and means to remove the same with the liners set. 110
12. The combination of a cylindrical liner form, means to apply a liner to be shaped thereon, an automatic folder having parts adapted to make folds with rounded parts across the end of said form, means for causing said liners to be enveloped within receptacles for lining same and means for removing said receptacles with the liners set. 115
13. In apparatus of the class described, the combination of a revoluble frame arranged to be continuously revolved, automatic devices for bending or folding enveloping material and means for supporting a receptacle intended to receive the folded enveloping material, the said devices and means carried by said frame. 120
14. In apparatus of the class described, the combination of a revoluble frame, a plurality of automatic receptacle forming means, a plurality of supports for pre-formed receptacles, said forming means and supports carried by said frame, and means for feeding preformed receptacles to said frame and to said supports. 125
15. In apparatus of the class described, the combination of a revoluble frame arranged to be continuously revolved, a plurality of mechanically operated devices for folding or bending enveloping material and a plurality of supports for receptacles intended to receive the folded enveloping material, said devices and supports carried by said frame. 130
16. In apparatus of the class described, the combination of a revoluble frame, a receptacle former and means for bringing a receptacle other than formed by said former into co-operation with said former, said means and former carried by said frame. 135
17. In apparatus of the class described, the combination of a revoluble frame, automatic devices for folding or bending enveloping material and means to bring a receptacle into co-operation with the enveloping material product of said devices, said means and devices carried by said frame. 140
18. In apparatus of the class described, the combination of a revoluble frame, a mechanically operated conveyor to deliver receptacles thereto, a receptacle support, automatically operated devices for folding or bending envelopment material, the said support and devices carried by said frame, and a mechanically operated conveyor to remove said receptacles therefrom. 145

19. In a machine for forming receptacles from flat pliable material, the combination of a former, means for rotating said former, means for imparting continuous translating motion to said rotatable former, means for spreading flat pliable material upon the shaping surface of said former during the rotation of the latter and means translating with said former for folding the pliable material into the shape of a receptacle while held by said former.

20. In a machine of the character described, the combination of means for imparting translating and rotary motion to pliable material, means for shaping said pliable material into the form of a receptacle during its motion of translation and rotation, a carrier for a second receptacle, means for imparting motion to said carrier and receptacle carried thereby and means for inserting said formed receptacle within the second receptacle during the motion of both.
